UNITED STATES PATENT OFFICE

JOHN W. SHIELDS, OF EVANSVILLE, INDIANA, ASSIGNOR TO FRED O. WEBER, OF
EVANSVILLE, INDIANA

HARDWARE FOR REVOLVING DOORS

Application filed July 22, 1931. Serial No. 552,496.

My invention relates broadly to revolving doors and more particularly to hardware for revolving doors arranged to permit the collapsing of the doors under excess pressure directed against the doors.

One of the objects of my invention is to provide a simplified construction of hardware for revolving doors having a minimum number of parts assembled in such manner that the hardware may be manufactured inexpensively on a quantity production scale.

Another object of my invention is to provide a construction of collapsible hinge for revolving doors whereby sets of revolving doors may be normally maintained in 90° relationship and under emergency conditions may be independently moved to a collapsed position in which the doors extend parallel to each other.

Still another object of my invention is to provide a construction of hinge for revolving doors having means for supporting the individual doors of the revolving door system in such manner that independent movement may be imparted to any one of the doors for moving the individual doors to different angular distances around a multiplicity of different pivots for shifting the doors under emergency conditions from positions normal to each other to collapsed positions parallel to each other.

A further object of my invention is to provide a construction of hardware for revolving doors in the form of disc members disposed adjacent the top and bottom of the revolvable shaft of a rotating door system where the discs have yoke members pivotally mounted therein in symmetrical relation, each of the yoke members having wing carriers pivoted therein for mounting the separate doors, the yoke members and wing carriers each having different paths of movement when shifted to different angular positions for allowing a collapsing of the several doors into parallel position under conditions of excess pressure exerted against the doors.

A still further object of my invention is to provide a simplified construction of hardware for revolving doors wherein discs fixed

to the revolving shaft of a door each support yoke members pivoted in symmetrical arrangement therein with wing carriers shifted to embrace the yoke members and pivoted with respect to the opposite extremities of the yokes so that the wing carriers may be moved in alignment with the yokes throughout an angular distance of approximately 45° about the pivot between the yoke and the supporting disc and thereafter disengaged from alignment with the yoke and independently moved through a distance approximately 90° whereby the several doors may be shifted from normal position to a position in which the doors are aligned in parallel arrangement.

A further object of my invention is to provide a construction of hardware for revolving doors in which a pair of hinge members may be disposed in horizontal planes adjacent the top and bottom of the door system and positively spaced by means of a tubular member extending between the hardware and concentrically disposed about the shaft which carries the several doors.

Other and further objects of my invention will be understood from the specification hereinafter following by reference to the accompanying drawings, wherein:

Figure 1 is a side elevation of the upper part of a revolving door system constructed in accordance with my invention; Fig. 2 is a horizontal sectional view taken substantially on line 2—2 of Fig. 1 with the wings extended at right angles to each other; Fig. 3 is a similar view with one pair of the wings partially collapsed and disposed in a parallel position to each other; Fig. 4 is a similar view showing all of the wings collapsed and moved into parallel positions with each other; Fig. 5 is a detailed top plan view of the base plate; Fig. 6 is a transverse vertical sectional view on an enlarged scale taken on line 6—6 of Fig. 4; Fig. 7 is a longitudinal sectional view on an enlarged scale taken substantially on line 7—7 of Fig. 2; Fig. 8 shows the assembly of the hardware with respect to the structure of the revolving door of my invention the view being taken in elevation on line 8—8 of Fig. 9; and Fig. 10

9 is a plan view of the revolving door structure equipped with the hardware according to my invention.

Referring to the drawings in detail reference character 1 designates the vertically disposed shaft which carries the revolvable door, adjacent the top and bottom of the movable door, on which I arrange the hardware shown in the drawings. The hardware 5 supports the several wings in predetermined 10 relation as illustrated. In order to attach the hardware to the wings I provide means extending from each of the wing supports and providing a socket through which the shaft extends. The sockets on the hardware members 15 are attached to the shaft by any suitable means such as screws extending radially through the sockets and engaging the vertically disposed shaft. In between the two hardware members there is a tubular shield 20 which extends over the shaft and provides longitudinally extending pockets into which the edges of the wings of the door fit. Each hardware member is provided with four leaf 25 hangers which are adapted to be locked in 90° relationship for maintaining the wings in operative position when the door is revolved. The leaf hangers however are arranged so that they may be collapsed in parallel relation under abnormal pressure against 30 the wings of the revolving door.

Each of the hardware members comprises a disc member 2 apertured at its center at 3 for the passage of the shaft 1. The disc 35 2 is preformed as shown in the plan view to enable the leaf hangers to be angularly shifted through an angular distance as large as 135° in collapsing the doors to a safety position under conditions of abnormal pressure 40 against the wings. The sockets 4 by which the disc 2 is secured rigidly to the shaft 1 is exteriorly formed with arcuate shaped faces designated at 5 in diametrically opposed positions with arcuate shaped faces 45 being spaced one from another by intermediate ribs 6. The arcuate shaped faces 5 are formed on a radius r extending from the center 7 in the disc 2. The screws 8 which pass through the socket 4 engage screw 50 threaded apertures in the shaft 1 for locating the disc in position with respect to the shaft 1. The discs 2 are mounted adjacent the top and bottom of shaft 1 and positively spaced by tubular member 27 which extends there- 55 between. The centers 7 are utilized as pivot points for the hinged yokes 9. There are four of these hinged yokes 9 which are angularly movable about centers 7 in the disc 2. Each yoke 9 has leg portions which em- 60 brace opposite sides of the disc 2 and an end portion 9a which provides a pivot means 11 for the wing 10 of the revolving door. The portion 9a of the yoke 9 has a plunger 12 mounted therein under control of the 65 spring 13 which tends to continuously urge

the plunger 12 radially inward for engaging sockets 14, 15 and 16 in the faces of the disc in predetermined angular positions in the edge of the disc 2 for maintaining the wing of the door in a predetermined angular position. That is to say, the several positions of the plunger with respect to the sockets enable the wings to be maintained in normal position or collapsed in either of two different directions as will be hereinafter described in more detail. The intermediate portions 17 of the disc 2 provide extreme limit stops for the yoke 9 in either of the extreme positions thereof. In order to shape the disc 2 to provide for the adjusting positions for the wings and the opposite limit stops, the disc 2 has its periphery formed on a radius r from the center 7 and the stops 18 and 19 having their faces extending radially from the center 7.

The wings are mounted uniformly about the disc in each of the leaf hangers. In their normal position where the leaves are disposed at 90° with respect to each other, the leaves are secured in the radial position shown in the drawings with plunger 12 entering socket 15. The wings while maintained in their normal position at 90° with respect to each other are readily collapsible under abnormal pressure. The immediately adjacent wings are collapsed toward each other from a position of 90° separation to a position where the wings extend parallel one with respect to another. This is accomplished by merely shifting the yokes about the pivots 7 and moving the plunger or detent 12 out of the center socket 15 and into the inner sockets 14 and 16, respectively. In bringing about this motion the inner edge of the leaf hangers 20 are free to move with respect to the arcuate shaped faces 5 of the socket 4 inasmuch as the edges of the leaf hangers 20 are formed on the same radius as the radius of the arcuate shaped faces 5 about the pivot point 7 of the yoke 9 as a center. The wings 21 and 22 which are moved into a parallel position adjacent each other are shifted so that the yokes 9 are moved in alignment with the leaf hangers 20. This alignment must be maintained in order to shift the wings 21 and 22 to a parallel position. The collapsing of the wings 21 and 22 is brought about by inward pressure upon the wings 21 and 22 toward each other, the yokes 9 pivoting about the pivot 7 as a center and allowing the interior edges of both yoke and wing hanger to pass in a predetermined path around the arcuate shaped face 5 on pivot 7 as a center.

With respect to wings 24 and 25, it is first necessary to rock the wing hangers in alignment with the yokes about pivots 7 as a center and thereafter the wing hangers are independently moved about the pivots 11 as a center on a radius R for shifting the wings 24 and 25 to the parallel position shown in

Fig. 4. That is to say, the wing hangers are first moved in alignment with the yokes 9 and thereafter disengaged from alignment with yokes 9 and given an independent movement allowing the four wings to have the same direction in collapsed position toward the point of egress from the building.

It will be observed that the pivots 11 extend through the wing hangers and into the sockets on each side of the yokes 9 as represented at 11a and 11b. The doors may be collapsed in either direction. When a direction of collapse opposite to the direction illustrated is required then the wings 21 and 22 are moved to a parallel position. In bringing about this movement the wing hangers 20 have an inward pressure applied thereto which serves to shift the wing hangers in aligned position with the yokes 9 from a position secured by detent 12 in socket 15 to a position where detent 12 enters socket 16 and 14 respectively, the yokes and wing hangers moving about pivot 7 as a center. It is then necessary to bring the opposite wings into collapsed position. This is accomplished by first moving the wing hangers and yokes in aligned position until the point of disengagement is reached, whereupon the wing hangers have independent movement about pivots 11 as a center allowing the wings to move through a further angle of 90° in assuming a position where the doors are collapsed in parallel arrangement in a direction opposite to the direction illustrated in the drawings.

It will be appreciated that under emergency conditions the revolving door may be in any angular position so that the collapsing operation heretofore described is not only possible in the two directions described but may also be carried out in the two directions normal to the directions just described, thus giving to the door structure a high degree of safety. It will be understood that the wings of the revolving door are normally maintained in 90° relationship by cables 26 as shown in Fig. 9 which can be released under abnormal pressure, which cables have been diagrammatically illustrated herein but which may take many different forms and which may be secured by a great many different structures of cable locks.

Fig. 8 shows the arrangement of the hardware wherein the socket portion of each hardware member is directed toward the top and bottom of the wings constituting the doors. The hardware is positively spaced by means of the tubular member 27 which is concentrically disposed about the tubular shaft 1. The tubular member 27 bears directly against the faces of the discs 2 which are opposite the faces of the discs 2 which carry the socket 4 and thus provides a positive means for spacing the discs 2 on the shaft 1 in addition to

the securing means 8 which are used to fasten the sockets 4 to the shaft 1.

The structure of my invention has many advantages over the prior principles among which I may mention the simplicity of the design herein and the capability of quantity production inexpensively. The number of parts in the structure of my invention has been reduced to a minimum as compared with complicated structures embodying gears and ratchet members heretofore employed in the art.

One of the principle advantages of my invention resides in the method by which the wing hangers is secured in position with respect to the yoke which connects with the supporting disc. Alignment of the yoke and the leaf hanger is automatically maintained through a displacement of 45° and then disengagement automatically brought about to permit movement of the wing through a further angle of 90° to the collapsed position of the wings.

I have found the construction of hardware according to my invention highly practical and while I have described one of the preferred embodiments of my invention I desire that it be understood that modifications may be made and that no limitations upon my invention are intended other than are imposed by the scope of the appended claims.

What I claim as new and desire to secure by Letters Patent of the United States is as follows:

1. A revolving door structure including a plurality of radially disposed wings, a vertically disposed shaft member, and means for supporting said wings with respect to said shaft member comprising a disc member secured to said shaft member adjacent the top and bottom of said door structure, yoke members having arms extending on opposite sides of each of said disc members and pivoted at spaced intervals around said discs, sockets carried by said discs centrally thereof, wing carriers connected to the inner peripheries of said wings, said wing carriers being pivotally connected to the outer ends of said yokes remote from the connection of said yokes with said discs for movement independent of the yokes and having portions projecting inwardly of the discs to engage in said sockets and releasably hold the carriers against movement independent of the yokes during movement of the yokes about the pivots carried by the discs.

2. A revolving door structure including a plurality of radially disposed wings, a vertically disposed shaft member, and means for supporting said wings with respect to said shaft member comprising a disc member secured to said shaft member adjacent the top and bottom of said door structure, yoke members having arms extending on opposite sides of each of said disc members and adjacent

their inner ends pivoted at spaced intervals around said discs, wing carriers connected to the inner peripheries of said wings, said wing carriers being pivotally connected to the outer ends of said yokes remote from the connection of said yokes with said discs, means carried by said discs to engage inner ends of said carriers and normally prevent independent movement of the yokes and carriers, said wing carriers being shiftable in alignment with said yokes about the pivots of said yokes on said discs through an angular distance of approximately 45° and being subsequently shiftable about the pivots between said wing carriers and said yokes as centers through a distance of approximately 90° to a position wherein said wings extend parallel.

3. A revolving door structure comprising a vertically extending shaft, discs secured adjacent the top and bottom of said shaft, a tubular member concentrically disposed about said shaft and arranged between said disc members for positively spacing said disc members one from another, yoke members pivoted adjacent their inner ends in symmetrical alignment on said discs and having their outer end portions extending beyond the periphery of the disc, sockets carried by said discs and having seats to receive inner ends of the yokes, wing carriers each pivotally mounted on the projecting portion of a yoke, a door mounted in each of said wing carriers, said yokes normally having their inner ends engaged in said seats and being shiftable with respect to said discs with said wing carriers in alignment therewith to a position for disengaging the wing carriers from the seats and permitting independent shifting the wing carriers about the pivots on the projecting portions of said yokes for collapsing the doors to parallel positions.

4. In a revolving door, a vertically disposed shaft, a hardware member carried by said shaft adjacent the top and bottom of the door, each of the hardware members including a disc having a set of yokes pivoted symmetrically thereon adjacent their inner ends and extending beyond the limits of the hardware member, a wing carrier pivoted adjacent the outer end of each of said yokes, means carried by said disc to engage the inner ends of the wing carriers when parallel to the yokes and preventing independent movement of said wing carriers with respect to said yokes within a range of movement of the wing carriers of approximately 45° , said wing carriers being disengageable from said means after such movement and angularly movable about the pivot near the outer ends of said yoke through a distance of approximately 90° independent of the movement of said yokes about the pivots on said disc.

5. A revolving door structure including a plurality of radially disposed wings, a verti-

cally disposed shaft member, and means for supporting said wings with respect to said shaft member comprising a disc member secured to said shaft member adjacent the top and bottom of said door structure, a tubular member disposed about said shaft member and abutting at opposite ends with said disc members, yoke members having arms extending on opposite sides of each of said disc members and pivoted in symmetrical positions around said discs, wing carriers connected to the inner peripheries of said wings, said wing carriers being pivotally connected to the outer ends of said yokes remote from the pivotal connection of said yokes with said discs whereby each of said wings has a radius of gyration about either of two separate centers, and means carried by said disc to engage the inner ends of the wing carriers and prevent independent movement of the yokes and wing carriers while the yokes are turning about pivots of the disc.

6. A revolving door structure including a plurality of radially disposed wings, a vertically disposed shaft member, and means for supporting said wings with respect to said shaft member comprising a disc member secured to said shaft member adjacent the top and bottom of said door structure, yoke members having arms extending on opposite sides of each of said disc members and pivoted at spaced intervals around said discs, wing carriers connected to the inner peripheries of said wings, said wing carriers being pivotally connected to the outer ends of said yokes remote from the pivotal connection of said yokes with said discs, means on said disc members for engaging the inner ends of the carriers and establishing an interlock while said wing carriers and said yokes are radially aligned within an angular distance of 45° , the carriers being movable out of engagement with the interlocking means when said wing carriers are moved beyond said angular distance, whereby each of said wings is independently shiftable about the pivot of said yoke members on said discs or the pivot of said wing carriers on said yokes through different angular distances to a position wherein said wings extend in parallel planes.

7. A revolving door structure including a plurality of radially disposed wings, a vertically disposed shaft member, and means for supporting said wings with respect to said shaft member comprising a disc member secured to said shaft member adjacent the top and bottom of said door structure, yoke members having arms extending on opposite sides of each of said disc members and adjacent their inner ends pivoted symmetrically around said discs, yieldable latches carried by said yoke members and projecting radially inward for engaging detents in the periphery of said disc members, wing carriers connected to the inner peripheries of said wings, said

wing carriers being pivotally connected to the outer ends of said yokes remote from the connection of said yokes with said discs, said wing carriers normally having their inner ends engaged in seats formed centrally of the disc and being shiftable simultaneously with the movement of said yokes about the pivots on said discs through a predetermined angular distance until inner ends of the yokes and wing carriers move out of the seats and then having independent angular movement about the pivots near the outer ends of said yokes through an additional angular distance.

8. A revolving door structure including a plurality of radially disposed wings, a vertically disposed shaft member, and means for supporting said wings with respect to said shaft member comprising a disc member secured to said shaft member adjacent the top and bottom of said door structure, yoke members having arms extending on opposite sides of each of said disc members and symmetrically pivoted around said discs, the periphery of said disc members adjacent each of said pivoted connections being formed on a uniform radius terminating in abutments for limiting the path of movement of said yoke members, wing carriers connected to the inner peripheries of said wings, said wing carriers being pivotally connected to the outer ends of said yokes remote from the connection of said yokes with said discs, said wing carriers being shiftable in alignment with said yokes as a unit therewith about the pivots near the inner ends of said yokes on said discs through an angular distance of approximately 45° and being subsequently shiftable about the pivots between said wing carriers and pivots near the outer ends of said yokes as centers through a distance of approximately 90° to a position wherein said wings extend parallel.

9. A revolving door structure comprising a vertically extending shaft, a disc member secured adjacent the top and bottom of said shaft, a tubular member concentrically disposed about said shaft and arranged between said disc members with its ends bearing against the same for positively spacing said disc members one from another, yoke members pivoted adjacent their inner ends in symmetrical alignment on said discs and each having a projecting portion thereon extending beyond the periphery of the discs, the peripheral edges of said discs being formed on radii having each of the adjacent pivot points as centers and spaced from each other by outwardly extending projections forming shoulders for limiting the path of movement of said yokes, wing carriers pivotally mounted adjacent the outer ends of the projecting portion of the yokes and straddling the yokes, a door mounted on each of said wing carriers, said yokes being shiftable about the inner pivots with respect to

said discs with said wing carriers in alignment therewith to a position for disengaging the wing carriers from the yokes for independently shifting the wing carriers about the pivots on the projecting portions of said yokes for collapsing the doors to parallel positions.

10. In a revolving door, a vertically disposed shaft, a hardware member carried by said shaft adjacent the top and bottom of the door, each of the hardware members having a set of four yokes pivoted symmetrically thereon and extending beyond the limits of the hardware member, curved peripheral edges being formed upon said hardware member on a radius having the pivot points of said yokes as centers and terminating in outwardly projecting opposite limiting abutment extending radially from the curved peripheral edges, a wing carrier pivoted upon the projecting portion of each of said yokes, a socket member connected with each of said hardware members for preventing independent movement of said wing carriers with respect to said yokes within a range of movement of the wing carriers of approximately 45° , said wing carriers being disengageable from said socket members and angularly movable about the pivot on said yoke through a distance of approximately 90° independent of the movement of said yokes about the pivots on said hardware members.

In testimony whereof, I affix my signature.

JOHN W. SHIELDS.
